UNITED STATES PATENT OFFICE.

JOHN T. SIMPSON, OF NEWARK, NEW JERSEY.

REINFORCING DEVICE FOR CONCRETE STRUCTURES.

No. 903,903.

Specification of Letters Patent.

Patented Nov. 17, 1908.

Application filed July 11, 1908. Serial No. 443,063.

To all whom it may concern:

Be it known that I, JOHN T. SIMPSON, a citizen of the United States, and residing at Newark, in the county of Essex and State 5 of New Jersey, have invented certain new and useful Improvements in Reinforcing Devices for Concrete Structures, of which the following is a specification, such as will enable those skilled in the art to which it 10 appertains to make and use the same.

My present invention consists of an improved reinforcing metal device for use in slabs, beams, girders, columns, partitions, arches, walls and the like, of concrete, which 15 can be strengthened and cheapened by the introduction of a reinforcing element to provide for tension and shearing stresses.

The objects of this invention are to provide a metal reinforcing device of the class 20 specified formed from a rolled shape, and consisting of a unit in which the total area of the device is used to provide for the tension stresses at the center near the bottom of the reinforced member, where the tension 25 stresses are generally maximum, and at the same time to form a trussed frame or device in which a part of the area is used to provide for the horizontal and vertical shearing stresses near the ends of the reinforced member 30 where the shearing stresses are generally maximum, and all the parts of which device are firmly attached to each other without resorting to a mechanical, electrical, chemical or other means of attachment, thus providing a reinforcing device of the class 35 specified in which there are no loose bars, rods or other parts which through carelessness or ignorance of workmen may be omitted during the installation, thus weakening 40 the construction; a further object of my invention being to provide a reinforcing device of the class specified formed from a rolled shape or unit, which can be kept in stock for distribution and from which reinforcing devices to suit any given requirements 45 of reinforcing can be quickly made and delivered, thus eliminating long and costly delays and which devices can be made singly or in multiples and which when made in single units can be readily made into multiple units by the use of clamps or other similar devices when the stresses in the

member which is being reinforced requires more area of metal than is provided in a single unit.

The invention is fully disclosed in the following specification, of which the accompanying drawing forms a part, in which the separate parts of my improvement are designated by suitable reference characters in 60 each of the views, and in which;

Figure 1 is a cross sectional view of a concrete structure showing my improved reinforcing device embedded therein; Fig. 2 a side view of the rolled shape or unit from 70 which the reinforcing device is made; Fig. 3 a view similar to Fig. 2 but on a larger scale and showing one step in the process of forming the reinforcing device from said rolled shape or unit; and, Fig. 4 a transverse 75 section on the line 4-4 of Fig. 3, but on a still larger scale.

In Fig. 1 of the drawing I have shown a concrete structure *a* such as is usually employed in the floor and ceiling work of 80 buildings, that part of said floor and ceiling work shown involving two I beams *a*² between which is placed my improved reinforcing device.

My improved reinforcing device is formed 85 from a rolled shape or unit *b* shown in Figs. 2, 3 and 4 and consisting of three parallel bars *b*², *b*³ and *b*⁴ connected by webs *b*⁵ and *b*⁶ all of said bars and webs being in the same plane, the webs *b*⁵ and *b*⁶ being also 90 much thinner than said bars, and the central bar *b*³ being preferably of less transverse dimensions than the side bars *b*² and *b*⁴.

In practice the web members *b*⁵ and *b*⁶ are sheared to form longitudinal and transverse 95 slits at the opposite sides of the central portion of the device, the method of shearing one end portion of said webs being clearly shown in Fig. 3, in which only one end portion of the device is shown, the longitudinal 100 portions of the slits being shown at *c* and the transverse portions at *c*², said transverse portions extending through the central bar *b*³ of the rolled form or unit.

In the construction shown there are three 105 of the longitudinal and transverse slits in each end portion of the reinforcing device, and adjacent to the central portion of the device one of the webs, the web *b*⁵, is slotted

longitudinally only as shown at a^3 , and when the webs b^5 and b^6 are slitted in the manner described the end portions of both webs and the end portions of the central bar b^3 are cut out as shown at d in Fig. 3, after which the end portions of one of the side bars are expanded or separated from the end portions of the other side bar as clearly shown in Fig. 1, the said end portions of the side bars being connected by diagonal rib members e formed by slitting the webs b^5 and b^6 longitudinally, and the central bar b^3 transversely as shown in Fig. 3. It will also be seen that the end portions of the separated or expanded side bars are parallel, and the middle portions thereof are also parallel, but the middle portion of the reinforcing device is of the width of the original rolled shape or unit only, whereas the end portions of the reinforcing device are much wider, and in expanding one of the side bars as shown in Fig. 1 the parts thereof adjacent to the central portion of the device are curved outwardly and in the direction of the ends of the device as shown at f .

One method of using my improved reinforcing device is clearly shown in Fig. 1, in which the ends of the bar b^6 overlap the I beams a^2 and are provided with hooks g which engage said beams, but it will be understood that my improved reinforcing device may be connected with the beams a^2 in any desired manner, and the said reinforcing device may be used in many positions and in many other forms of concrete constructions.

The device described and claimed herein is an improvement on that described and claimed in a prior application filed by me Dec. 17, 1907, Ser. #406,864, and, in practice, the reinforcing device described and claimed herein may be used single as shown and described, or it may be used in multiple units as shown and described in said prior application and in the same relations and for the same purposes described and claimed in said prior application.

In the accompanying drawing the bars b^2 , b^3 and b^4 are shown as cylindrical in cross section, but said bars may be of other shapes in cross section if desired.

Having fully described my invention what I claim as new and desire to secure by Letters Patent, is:—

1. A metal reinforcing device for use in concrete constructions composed of three parallel bars connected by webs of less thickness than said bars, the said webs at the opposite sides of the central portion of the device being slitted longitudinally and transversely at intervals, the transverse portions of said slits extending through the central bar, and the end portions of one of the side

bars being expanded or separated from the end portions of the other side bar and being connected therewith by diagonal members formed from the central bar.

2. A metal reinforcing device for use in concrete constructions composed of three parallel bars connected by webs of less thickness than said bars, the said webs at the opposite sides of the central portion of the device being slitted longitudinally and transversely at intervals, the transverse portions of said slits extending through the central bar, and the end portions of one of the side bars being expanded or separated from the end portions of the other side bar and being connected therewith by diagonal members formed from the central bar, said central bar being also of less transverse dimensions than the side bars.

3. A metal reinforcing device for use in concrete constructions composed of three parallel bars connected by webs of less thickness than said bars, the said webs at the opposite sides of the central portion of the device being slitted longitudinally and transversely at intervals, the transverse portions of said slits extending through the central bar, and the end portions of one of the side bars being expanded or separated from the end portions of the other side bar and being connected therewith by diagonal members formed from the central bar, said central bar being also of less transverse dimensions than the side bars, and the slits in one of the web members adjacent to the central portion of the device being longitudinal slits only.

4. A metal reinforcing device for use in concrete constructions composed of three parallel bars connected by webs of less thickness than said bars, the central bar being also of less transverse dimensions than the side bars, but said webs at the opposite sides of the central portion of the device being slitted longitudinally and transversely at intervals, the transverse portions of said slits extending through the central bar, and the end portions of one of the side bars being expanded or separated from the end portions of the other side bar and being connected therewith by diagonal members formed from the central bar.

5. A metal reinforcing device for use in concrete constructions composed of three parallel bars connected by webs of less thickness than said bars, the central bar being also of less transverse dimensions than the side bars, but said webs at the opposite sides of the central portion of the device being slitted longitudinally and transversely at intervals, the transverse portions of said slits extending through the central bar, and the end portions of one of the side bars being expanded or separated from the end portions

of the other side bar and being connected therewith by diagonal members formed from the central bar, the slits in one of the webs adjacent to the central portion of the device 5 being longitudinal slits only.

In testimony that I claim the foregoing as my invention I have signed my name in

presence of the subscribing witnesses this 10th day of July 1908.

JOHN T. SIMPSON.
